CLAIM

The ornamental design for a tail lamp for a vehicle, as shown and described.

DESCRIPTION

FIG. 1 is a front perspective view of a first embodiment of a tail lamp for a vehicle showing our new design.

FIG. 2 is a rear and bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a right side elevational view thereof showing environmental structure.

FIG. 10 is a front perspective view of a second embodiment of a tail lamp for a vehicle showing our new design.

FIG. 11 is a rear and bottom perspective view thereof.

FIG. 12 is a front elevational view thereof.

FIG. 13 is a rear elevational view thereof.

FIG. 14 is a left side elevational view thereof.

FIG. 15 is a right side elevational view thereof.

FIG. 16 is a top plan view thereof.

FIG. 17 is a bottom plan view thereof; and,

FIG. 18 is a right side elevational view thereof showing environmental structure.

Stippling and contour lines shown in FIGS. 1-18 are intended to represent approximate three-dimensional contours of the design, and are not intended to indicate surface decoration. The broken lines in FIGS. 1-18 are for the purpose of illustrating environmental structure for the claimed design and form no part of the claimed design.

The stippling shown in FIGS. 1-9 is intended to represent transparent surfaces of the design, and are not intended to indicate surface decoration. The stippling of these same surfaces in FIGS. 10-18 is intended to represent transparent surfaces of the design, and are not intended to indicate surface decoration.

The stippling in FIGS. 10-18 that is not in FIGS. 1-9 is intended to represent translucent surfaces of the design, and are not intended to indicate surface decoration.
